UNITED STATES PATENT OFFICE.

JESS L. BURNS, OF FARNHAMVILLE, IOWA.

PORTABLE STALK-GUARD FOR BINDERS.

1,291,760.

Specification of Letters Patent. Patented Jan. 21, 1919.

Application filed October 16, 1916, Serial No. 125,929. Renewed June 3, 1918. Serial No. 238,044.

To all whom it may concern:

Be it known that I, JESS L. BURNS, a citizen of the United States, residing at Farnhamville, in the county of Calhoun, State 5 of Iowa, have invented certain new and useful Improvements in Portable Stalk-Guards for Binders; and I do hereby declare the following to be a full, clear, and exact description of the invention, such as will enable others skilled in the art to which it 10 pertains to make and use the same.

This invention relates to attachments for binders and has special reference to a portable stalk guard for binders.

15 It is an object of the present invention to provide a device which will cure a difficulty resident in binders of certain types.

In some binder constructions, there is employed a flat platform arranged behind the 20 cutter bar longitudinally thereof, over which there passes the usual platform canvas, which is mounted on rollers at the ends of the platform. There is an open space at the end of the platform, and the difficulty referred to arises from the fact that during 25 operation of the mechanism, the lower portion of the canvas, traveling toward the outer end of the platform engages and carries with it stray stalks of grain which may 30 have escaped the cutter bar. There is a transverse brace rod at the inner end of the platform, which extends above the platform surface and it is often the case that stalks carried by the lower portion of the canvas 35 become clogged between this brace rod and the canvas itself, seriously interfering with the operation of the machine. The present device is provided to prevent such clogging and interference with the operation of the 40 machine.

An important object of the invention is the provision of a portable stalk guard of this description which is adjustable to various widths of platforms and which may be 45 connected to various binders by means of hooks and straps in such manner that, while always remaining close to the platform canvas, the other edge of the guard may be suspended to any of the braces of the machine 50 at a distance from the platform by means of adjustable straps.

With the above and other objects in view, as will be hereinafter apparent the invention consists in general of certain novel 55 tails of construction and combinations of parts hereinafter fully described, illustrated

in the accompanying drawing, and specifically claimed.

In the accompanying drawing, like characters of reference indicate like parts in the 60 several views, and:—

Figure 1 is a perspective view of a portion of a binder and its platform showing the device applied thereto.

Fig. 2 is a top plan view of the device. 65

Fig. 3 is an end view of the device.

Fig. 4 is a section on the line 4—4 of Fig. 2.

In the embodiment of the invention herein illustrated there is provided a pair of 70 trough-shaped plates 10 and 11 each of which has its lateral edges inturned, the edges of the plate 10 being indicated at 12 while the edges of the plate 11 are indicated at 13. The inturned edges of the plate 10 75 slidably engage in the inturned edges of the plate 11 so that the plates are thus slidably connected. Along one set of these inturned edges are arranged hooks 14 which, it will be noted, open downwardly when the device 80 is in operative position. Along the other edges 12 and 13 are provided pivoted loops 15 through which extend straps 16 carrying at one end a buckle 17 while the other end is provided with suitable perforations 85 of the usual class for the reception of the buckle tongue.

By reference to Fig. 1 it will be seen that the binder A is provided with main frame braces a and a transverse brace rod b, the 90 platform canvas being shown at Z. In use the hooks 14 are engaged on the transverse brace rod b and the parts 10 and 11 slid longitudinally of each other until they fit between the sides of the machine. The 95 straps are then connected to the main frame braces a so as to hold the plates substantially horizontal or with their strap carrying edge somewhat elevated.

It will thus be seen that any stalks remaining uncut and lying inwardly of the end of the harvester platform, which is indicated at X in the drawings, will be prevented from engagement with the canvas Z by the present device. 100

The present device has another function, in that, being disposed at the end of the platform canvas, it lies below the vertical elevator of the harvester (not shown). It is well known that, when the mechanism of 110 the harvester is thrown out when the machine is turned at corners, or when the ele-

vator ceases to move as a result of differential action of the ground wheels of the machine, stalks of grain are sometimes engaged between the canvases of the vertical elevator only by their stalks, and, the heads being heavier, the weight thereof tends to drag the stalks from the elevator and permit these stalks to fall to the ground. The present device, being located in a position to lie beneath the vertical elevator, will receive the heads of the grain thereagainst and prevent sufficient movement thereof to disengage their stalks from the vertical elevator.

There has thus been provided a simple and efficient device of the kind described and for the purpose specified.

It is obvious that many minor changes may be made in the form and construction of the invention without departing from the material principles thereof. It is not therefore desired to confine the invention to the exact form herein shown and described but

it is wished to include all such as properly come within the scope claimed.

What is claimed is:

A portable stalk guard for binders comprising a pair of trough shaped plates having inturned edges, the inturned edges of one plate fitting in the inturned edges of the other plate to slidably connect the two plates, hooks arranged along the inturned edges on one side and opening downward when in position of use to engage over a brace rod on a binder, loops pivotally connected to the inturned edges on the other side, and flexible buckle provided straps extending through the loops for detachable connection to brace members of the binder.

In testimony whereof, I affix my signature, in the presence of two witnesses.

JESS L. BURNS.
